Primary Examiner — Rashida Johnson(74) *Attorney, Agent, or Firm* — Amster, Rothstein & Ebenstein, LLP(57) **CLAIM**

The ornamental design for a dress/coat, substantially as shown and described.

DESCRIPTION

FIG. 1 is a front elevational view showing my new design;
FIG. 2 is a rear elevational view thereof;
FIG. 3 is a left side elevational view thereof;
FIG. 4 is a right side elevational view thereof;
FIG. 5 is a top plan view thereof; and,
FIG. 6 is a bottom plan view thereof.

The broken lines in FIG. 6 represent the portions of the design, which form no part of the claim.
